PANTS HANGER

Filed Jan. 30, 1928

UNITED STATES PATENT OFFICE

CARL T. BATTIS, OF GRAND RAPIDS, MICHIGAN

PANTS HANGER

Application filed January 30, 1928. Serial No. 250,362.

This invention relates to a pants hanger adapted to be applied to a conventional construction of coat hanger. It is a primary object and purpose of the present invention 5 to provide an exceptionally simple and economically constructed pants hanger including a rod of larger cross sectional area than the wire usually used for such purpose, mounting the same in a particularly simple 10 and effective manner.

An understanding of the invention will be had from the following description taken in connection with the accompanying drawing, in which,

15 Fig. 1 is a perspective view of a combined coat and pants hanger, the pants hanger being made in accordance with my invention.

Fig. 2 is a side elevation of the pants hanger showing the rod thereof disconnected 20 at one end.

Fig. 3 is a plan view of said hanger, and

Fig. 4 is a fragmentary perspective view illustrating the various parts which are used in the construction of said pants hanger.

25 Like reference characters refer to like parts in the different figures of the drawing.

The coat hanger with its arms 1 diverging downwardly and outwardly from its middle point where the usual suspending hook 2 is connected, is of any conventional form and the construction thereof specifically forms 30 no part of the present invention.

In the construction of the pants hanger, a wire rod 3 is provided which at one end is 35 bent downwardly and outwardly at an angle making an inclined section 4 which terminates in a loop 5 through which a screw may be passed to secure one end of the rod permanently at the under side of and adjacent the outer end of one of the arms 1 of the coat hanger. Closely adjacent the bent part of the section 4 and the main body of the rod 3 the metal is flattened for a short distance, as indicated at 6. The rod 3 extends toward 45 the opposite arm of the coat hanger and a short distance therefrom is bent into a U-shaped loop or socket 7 open at its upper side, being thence continued until it reaches the underside of the opposite arm of the coat hanger where it is bent downwardly and out-

wardly at an angle and formed into a loop 8 through which a second screw is passed to fasten the opposite end of the rod 3 to the underside of the other arm of the coat hanger near its outer end. 55

A U-shaped stirrup or clip of sheet metal having a bottom 9 and two vertical spaced apart legs 10 and 11 is designed for mounting on the rod 3 near one end thereof. Near the upper end of the leg 10 a slotted opening 12 is made through which the rod 3 may freely pass, while in the upper end of the opposite leg 11 a vertical slot 13 is made in which the flattened section 6 of rod 3 seats. This mounts the stirrup member on the rod 3 60 and holds it against moving over the rod or turning about said rod. 65

A circular opening 14 is made in the leg 10 below the slot 12 therein, first described and joining therewith, and a second circular opening 15, in axial alignment with the opening 14 but of smaller size, is made through the leg 11. A rod 16 of wood, considerably larger in cross section than the rod 3, passes at one end through the opening 14 and has a reduced end 17 which is received in the opening 15 as shown. After the rod is assembled with the clip, the edges of the leg 10 are struck, bending and pressing the same inward and firmly engaging with and pressing 70 into the sides of the rod 16, to hold the same 75 from disengagement.

The free end of the rod 16 is designed to be received in the U-shaped socket 7 of the wire rod 3. The free end of the wood rod 16 80 may be lifted above the socket 7 so as to disengage therefrom. In practice the engagement of the free end of the rod 16 in the socket 7 twists the supporting clip and slightly 85 flexes the rod 3 imparting a tension which, when the end of the rod 16 is freed from the socket, tends to throw the rod 16 away from the socket after which it will drop freely by gravity to the position shown in Fig. 2, providing plenty of space for the placing of 90 pants over the rod 16. The rod 3 lying for a part of its length directly over the rod 16 95 serves to press against the garment and hold it against accidental displacement.

The construction described is very eco- 100

nomical to manufacture consisting of three parts only, the rods 3 and 16 and the U-shaped metal clip. By reason of the slotted opening 12 joining with the larger opening 14 it is easy to assemble the wire rod 3 with the loop 5 formed at its end and all the parts may be completely fabricated before assembly so that the only operation done after assembly is to pinch the sides of the leg 10 of the clip against the wood rod 16 as previously described. The U-shaped stirrup member after assembly is held from any movement along the rod 3 on which it is mounted.

15 The claims appended hereto define the invention which is to be considered comprehensive of all forms of structure coming within the scope thereof.

I claim:

20 1. A pants hanger comprising, a wire rod having means at its ends adapting it for attachment to a coat hanger, said rod adjacent one end thereof being formed into a U-shaped seat open at its upper side, a U-shaped sheet metal stirrup mounted on the rod adjacent the other end thereof and depending below the same, and a second rod larger in cross sectional area than said wire rod having one end thereof connected with said stirrup below said wire rod, the opposite free end of said second rod being adapted to detachably connect with said seat for the purposes described.

35 2. A pants hanger comprising, a rod adapted to be connected at its ends to the arms of a coat hanger, said rod near one end thereof being bent into a vertically positioned U-shaped seat open at its upper side located transversely to the length of said rod, a fixture mounted near the opposite end of said rod and depending below the same, and a second rod having larger cross sectional area than the first rod carried at one end by said fixture below the first rod, the opposite end of said second rod being adapted to be removably received within said seat.

50 3. A pants hanger comprising, a wire rod adapted to be secured at its ends to the lower sides of the diverging arms of a coat hanger, said rod adjacent one end being formed into a transversely located U-shaped seat and adjacent its other end having a short vertically positioned flattened portion, a U-shaped stirrup of sheet metal mounted on said wire rod, one of the legs of said stirrup having an opening through which the rod passes and the other leg having a vertical slot in its upper end in which the flattened portion of said wire rod is received, and a second rod connected at one end to said stirrup below the first rod, the opposite end of said second rod being detachably received within said seat.

55 4. A pants hanger, comprising, a metal rod formed adjacent one end with a transversely disposed U-shaped seat open at its

upper end, a U-shaped stirrup of sheet metal mounted adjacent the opposite end of said rod and depending therefrom, means for holding the stirrup against movement along said rod or rotative movement about said rod, the legs of said stirrup at points below said rod having openings therethrough, and a second rod passing through the opening in one of the legs in said stirrup and at its end having a reduced section entering the opening of the other leg of said stirrup, said second rod at its opposite end detachably seating in said transverse seat.

60 5. A pants hanger comprising a wire rod bent near one of its ends to form a transverse, upwardly opening, integral seat, a second rod extending below said wire rod and having one of its ends removably supported on said seat, means associated with the wire rod near the end opposite the seat for attaching an end of the second rod and supporting said second rod below the wire rod for limited movement of its unconnected end.

65 6. A pants hanger comprising a horizontal wire rod, a second rod of compressible material located below and substantially parallel with said wire rod, means at one end of said rods for connecting them together, said means being pressed into said second rod for retention therein and means at the opposite ends of said rods for detachably connecting them together.

In testimony whereof I affix my signature.

CARL T. BATTS.
